UNITED STATES PATENT OFFICE

LEWIS J. BAZZONI, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

MACHINE FOR APPLYING FOXING TO SHOES

Application filed August 3, 1926. Serial No. 126,889.

This invention relates to machines for use in the manufacture of boots and shoes and is herein illustrated as embodied in a machine for applying a foxing to a lasted tennis shoe 5 or the like.

In the manufacture of rubber-soled footwear having fabric uppers, such as a tennis shoe or an arctic, in which the sole is vulcanized to the upper it is customary, after the 10 shoe has been lasted but before the unvulcanized sole has been attached, to lay a narrow strip of unvulcanized rubber, commonly known as a foxing, along the junction of the bottom with the sides of the shoe in such manner that the strip is bent at right angles about a line parallel to its length and adheres partly to the bottom and partly to the lower side portions of the shoe. After the foxing has been 15 thus applied and the usual filler placed on the bottom of the shoe, the unvulcanized rubber sole is laid, and the shoe vulcanized. The foxing not only gives a neat appearance to the shoe, but ensures a tight joint between the upper portion of the shoe and the sole.

20 A machine for applying foxing is disclosed in Patent No. 1,439,794, granted December 26, 1922 upon an application filed in the name of Casgrain. This machine comprises a supply reel for a coiled strip of unvulcanized foxing 25 having intercoiled therewith a strip of backing made of paper or fabric, the two-ply strip being led to the shoe where, by pressure applied through the backing, the foxing is caused to adhere to the shoe, the backing strip 30 being subsequently pulled away from the foxing and wound upon a winding-up reel. In the use of machines of this general type in which the foxing is supplied in the form of a long strip, it is necessary to sever the foxing 35 at or near the end of the applying operation; and hitherto this severing has been performed by hand.

40 According to one feature of the present invention, means are provided for severing the foxing. In the illustrative machine, this means takes the form of a pair of shears which are normally open and in inoperative position at one side of the path of the foxing as it travels from the supply reel to the shoe, 45 operator-controlled means being provided for

first moving the shears to operative position and for then closing them to sever the foxing.

50 In order to prevent the backing strip from being severed at the time the foxing is severed as well as to facilitate the proper applying of the foxing to the shoe, another feature of the invention comprises a construction whereby the backing strip is separated from the foxing before the two-ply strip reaches the severing means. In the illustrative construction, the 55 two-ply strip shortly after it leaves the supply reel is separated, the foxing traveling to the shoe and the backing strip to the winding-up reel. The shears, mentioned above, are located adjacent to the locality in which the 60 shoe is presented to the machine and operate, as has been explained, to sever the foxing only. The backing strip thus remains intact, serves to pull the two-ply strip from the supply reel when foxing is being applied to the 65 succeeding shoe; and may subsequently be intercoiled with another supply of foxing and used again.

70 The foxing consists of a thin strip of unvulcanized rubber which may easily be deformed and is very sticky. No considerable pull should be exerted at any time upon the foxing, since such a pull would stretch and deform it; and, on the other hand, no slack should be allowed to occur in it with the consequent formation of bends which would bring two of the sticky surfaces of the foxing 75 into contact, since such surfaces would immediately adhere to each other. According to another feature of the invention the backing 80 strip is caused to be wound up at exactly the same rate that the foxing is applied to the shoe. In the illustrated construction, the foxing after having been separated from the 85 backing strip is led to an indenting wheel which serves, when a shoe with the free end of the foxing upon it is presented to said wheel and moved past it, to apply the foxing to the shoe. The backing strip is led from the point where it separates from the foxing to a 90 winding-up reel; and the whole construction is such that neither the foxing nor the backing strip is fed along except when foxing is being applied to the shoe at which time the backing 95 moves at the same speed as the foxing.

It is highly desirable that the foxing should be pressed into firm contact with the shoe so that it will adhere strongly and so that no air shall be entrapped beneath it. According, therefore, to another feature of the invention means is provided for hammering the foxing into place. In the illustrative construction a plurality of yielding hammers carried by a rotary head are caused successively to strike that portion of the foxing which lies on the lower side portion of the shoe and then to drag over that portion of the foxing which projects beyond the bottom of the shoe so as to bend said last-named portion over and press it against the bottom of the shoe.

These and other features of the invention, including certain details of construction and combinations of parts, will be described as embodied in an illustrative machine and pointed out in the appended claims.

Referring now to the accompanying drawings,

Fig. 1 is a perspective of a lasted shoe after the foxing has been applied;

Fig. 2 is an end elevation of a machine in which the present invention is embodied;

Fig. 3 is a plan of a portion of the foxing guide viewed in the direction indicated by the arrow in Fig. 6;

Fig. 4 is a perspective of the machine;

Fig. 5 is an elevation showing, more particularly, the foxing guide, a portion of the indenting wheel, and a portion of a shoe to which foxing is being applied; and

Fig. 6 is a front elevation of the machine.

Figs. 3 and 5 are on an enlarged scale as compared with the other figures.

Before proceeding with a detailed description of the machine, a brief description of its general mode of operation will be given. Mounted at the top of the machine is a supply reel carrying a coil of foxing 100 having intercoiled therewith a backing strip 200 of fabric. The backing strip travels down between the arms of a stationary fork 9 under a small roll 11, which holds the strip against a driven roll 13, over a roll 15, then down around a measuring wheel 17 the function of which will presently be described, and finally to a winding-up reel a rotary flange of which is indicated at 19. The foxing 100 travels down over a roller 21 into a guide 23, under a roll 51, over a crossbar 25 of the guide 23, under a small roll 26, under an indenting wheel 27, and finally to the shoe 300. The roll 13 and the winding-up reel are rotated through a friction drive, presently to be described, the strength of which is so regulated that, when no shoe is being presented to the machine, these members do not rotate. When, however, a shoe is presented to the machine after the manner shown in Figs. 2 and 5 and moved along so as to rotate the indenting wheel 27, the measuring wheel 17 is rotated and the

winding-up reel and the roll 13 are also rotated; and this rotation continues until the operator ceases to rotate the indenting wheel 27. The strip-engaging rolls, as will presently be explained more in detail, are so proportioned and driven that their surface speeds are equal to one another and to the surface speed of the indenting wheel 27. Consequently all portions of the foxing and the backing strip travel at the same speed. The foxing is thus fed to the shoe without strain and without the formation of slack. When the operator has moved the shoe along in the manner indicated in Figs. 2 and 5 until all of the desired foxing has been applied except a short length, he removes the shoe from operative relation to the indenting wheel and operates a pair of shears 29, 31 in a manner presently to be described to sever the foxing. He then lays the last end of the foxing by hand. A short length of the original strip of foxing is thus left hanging down from the guide 23 in position to be engaged by the next shoe which the operator presents to the indenting wheel. The foxing is applied to the shoe in such manner that the greater portion of it lies upon the lower side margin of the shoe but with a portion projecting beyond the bottom of the shoe. While the foxing is being laid in place in the manner which has been outlined above by presenting the shoe to the indenting wheel and moving the shoe along, a series of yieldingly mounted hammers 33 (see Fig. 2) strike the foxing where it is laid on the lower side margin of the shoe and wipe down across the bottom of the shoe, thereby bending the foxing around the junction of the side and bottom of the shoe to produce the effect best shown in Fig. 1. With this brief description of the general mode of operation of the machine, a detailed description of the parts will now be given.

The indenting wheel 27, which is toothed, serves to press the extreme upper margin of the foxing against the side of the shoe; and, in so doing, its teeth form a row of indentations in the foxing. This wheel 27 is rotatably mounted in a bracket 35 (see Figs. 4 and 6) and has rigid with it a pinion 37 which meshes with a pinion 39 also carried by the bracket, said pinion in turn meshing with a pinion 41 rigid with the measuring wheel 17 which is also carried by the same bracket 35, said bracket being adjustably fastened to the frame of the machine by cap screws, one of which is shown at 43. The moving parts which have just been described are so proportioned that the surface feed of the indenting wheel 27 and that of the measuring wheel 17 are equal so that the backing strip 200 travels at the same speed as the foxing 100 and no slack is formed in the foxing as would occur, for example, if the backing strip were pulled from the supply reel 7 faster than the foxing was applied to the shoe.

The formation of slack in the foxing would be liable to produce a very undesirable result, due to the fact that it is so sticky that, if loops were formed in it, they would adhere to one another so that the machine would presently have to be stopped while the operator straightened out the foxing.

The guide 23 (Figs. 5 and 4) is curved at its lower portion and has a vertical groove 45 in its upper portion to fit over a vertical guide formed on the bracket 35 so that the guide may be adjusted vertically. It is held in adjusted vertical position by a cap screw 46 which passes through a slot in the guide 15 and is threaded into the bracket 35. The guide has two pairs of lugs 47, 49 extending in a direction away from the indenting wheel. In the lower pair 49 are mounted two rolls 51, 53 between which the foxing 100 runs, and in the upper pair 47 is mounted a screw-threaded roll 55 against which the foxing runs. The purpose of the screw-threaded roll 55 is to crowd the foxing over toward the indenting wheel. Mounted in the inner one of the lugs 47 (see Fig. 4) is a small rod 57 upon which is slidably mounted the hub of an L-shaped member 59, held in adjusted position by a set screw 61. This L-shaped member is adjusted into a position dependent upon the width of the foxing 100. The roll 51 (see Figs. 2 and 5) is also threaded and of slightly conical form and acts as does the rod 55 to crowd the foxing over toward the indenting wheel. Across the extreme lower end of the guide 23 extends the bar 25, which has been referred to above; and the guide 23 is adjusted into such a position that the space between this bar and the indenting wheel is slightly less than the thickness of the foxing, so that the teeth of the indenting wheel engage the foxing to advance it when a shoe is being operated upon, and to prevent the foxing from slipping back out of guide when no shoe is being presented to the machine. Although for convenience the member 25 has been referred to as a bar extending across the extreme lower end of the guide 23, it will be seen by reference to Fig. 3 that the bar is not continuous but has a slot 63 through it, the purpose of the slot being to facilitate placing the free end of a new strip of foxing in proper position, since if the slot were not present it would be difficult to thread the free end of the foxing through the space between the indenting wheel and the guide. In order to make sure that the edge of the foxing shall not get out from beneath the indenting wheel, two further members are provided for engaging the opposite edge of the foxing, namely the end of a leaf-spring 65 (see Fig. 3), which may be adjusted by means of a screw 67, and a

small roller 69 carried at the end of an arm 71 which is pivotally attached to the guide 23 and may be clamped in adjusted position by a screw 73.

The hammers 33 (see Fig. 4) are pivoted at 75 between the arms 77 of a head which is fast to a shaft 79. These hammers are arranged in pairs connected by springs 81 (see Fig. 2) which engage at their opposite ends small arms 83 which are rigid with the hammers; and each hammer has a tail 85 which is normally held against a stop 87 by the action of its spring. Consequently, when the head is rotated in a clockwise direction as viewed in Fig. 2, each hammer first presses a portion of the foxing against the side of the shoe and then bends the remaining portion of the foxing down over the bottom of the shoe and presses it against said bottom. The hammers are so mounted that they clear the guide 23 and strike the foxing just inside the locality in which it has been pressed against the shoe by the indenting wheel. The shaft 79 (see Fig. 4) by which the hammer-carrying head is rotated has fast to it a gear 89 which meshes with a gear 91 fast on a shaft 93 which, like the shaft 79, is mounted in bearings in the frame of the machine. Fast to the shaft 93 is a sprocket 95 around which and around a sprocket 97 (Fig. 2) passes a chain 99. The sprocket 97 is fast to a shaft 101 rotatably mounted in the frame of the machine to which is also fast a worm wheel 103 which meshes with a worm 105 fast to a shaft 107 also rotatable in the frame of the machine. This shaft 107 is adapted to be driven by means of a pulley 109 through a friction clutch 111 which may be thrown into or out of action by swinging a fork 113. This fork is fast to a rock-shaft 115 to one end of which (see Fig. 4) is also fastened the hub of an arm 117, the free end of the arm having pivoted to it the upper end of a treadle rod 119 to the lower end of which is attached a treadle, not shown. A tension spring 121 normally holds the arm 117 up against a stop screw 123 in which position the friction clutch 111 is inoperative. It will be understood that when the operator presents a shoe to the indenting wheel and moves it along so as to lay the foxing on the shoe, he depresses the treadle so as to cause the hammers 33 to operate in the manner which has been described above.

The winding-up reel for the fabric backing strip has been referred to above with reference to the numeral 19. This numeral indicates a disk-like plate having a hole at its center and adapted to be clamped by means of a butterfly nut 125 to the end of a shaft 127 (see Fig. 2). The fabric strip 200 is wound upon a wooden hub which is also clamped to the shaft 127 by means of the same butterfly nut. Opposite the disk-like member 19 is a stationary member 129 of similar form having integral with it a hub 131 through which the shaft 127 extends, said

shaft being mounted in stationary bearings 133, 135. The hub 131 is fastened by pins (not shown) to the bearing 133. At the left of the bearing 133 is a flanged collar 137 fast 5 to the shaft 127 between which collar and the bearing 133 is a ball thrust 139. A coiled spring 141 extends between the collar 137 and a second collar 143 which is slideable on and keyed to the shaft 127 by a screw 145. 10 Loose on the shaft 127 is a third collar 147 having fast to it a pulley 149; and between the collars 147 and 143 is a friction washer 151. The pulley 149 is constantly rotated by means of a belt 153 which passes around 15 said pulley and around a pulley 155 on the shaft 101. The spring 141 is so chosen that the force supplied to the reel is insufficient to rotate the reel so long as no shoe is being presented to the machine. When, however, 20 a shoe is presented to the machine in such manner as to cause the indenting wheel 27 to rotate, the measuring wheel 17 is also rotated; and the reel is then rotated.

It has been stated above that the backing strip is wound upon the winding-up reel at 25 a speed which is the same at which the foxing is applied to the shoe. Referring now more particularly to Fig. 6 with occasional references to Fig. 4, the mechanism for feeding and winding-up the backing strip will now be described in detail. The surface speed of the small roll 13 should be equal to the surface speed of the coil of wound-up fabric; and, consequently, 30 this small roll is driven from the coil of fabric in the following manner. The shaft upon which the roll 13 is mounted has fast on its end a sprocket around which and around a sprocket 163 runs a chain 165. The 35 sprocket 163 is carried at the inner end of a shaft 167 which is rotatably mounted in a bearing 169, said bearing being carried at the outer end of two arms 171, the inner ends of which are pivoted about the shaft 173 of the roll 13. Fast to the outer end of the 40 shaft 167 is a spur wheel 175 which engages the coil of fabric on the winding-up reel. In order to hold this spur wheel down upon the coil of fabric, a lever 177 pivoted at 179 to 45 one of the arms 171 has hung upon its outer end by means of a hook 181 a weight 183. In order to aid in holding the fabric strip against the small roll 13 there is provided a roll 185 rotatably mounted at the lower end 50 of an arm 187, the hub at the upper end of which is rotatable on the rod 189 by which the fork 9 is carried. Fast to this hub is a second arm 191 between which and the frame 55 of the machine is a compression spring 193. A hook 195 is provided for engaging the arm 191 when desired, and thereby holding the roll 185 away from the roll 13. The parts 60 which have just been described are so proportioned and arranged that the roll 13 is 65 driven at a surface speed which is the same

as that of the spur gear; and the surface speed of the spur gear, it will be noted, is the speed at which the backing strip is wound up on the reel. This speed is the same as the surface speed of the measuring roll 17 which is rotated, as has been explained, at the same 70 surface speed as is the indenting wheel 27. It will be evident that, as the foxing is applied to the shoe at a speed dependent upon how fast the operator causes the indenting wheel 75 27 to rotate by engagement with the shoe, the backing strip 200 will be moved along at the same speed. The foxing 100, therefore, moves from the supply reel 7 to the work at exactly the rate at which it is applied to the 80 shoe.

By abruptly changing the direction of movement of the backing strip at the point at which it passes over the fork 9 (Fig. 6), the separation of the backing strip from the foxing is facilitated; and, in order to make sure that such separation takes place, a roll 157 is provided the shaft of which (Fig. 4) has fast at its outer end a gear 161 which meshes with a gear 159 of equal size on the shaft of the 90 roll 13. The two rolls thus rotate in opposite directions at the same surface speed. If at any time the separation of the backing strip and the foxing does not take place in the manner shown in Fig. 6, the foxing will contact 95 with the roll 157 which will serve to cause such separation.

Referring now more particularly to Fig. 4, the blade 29 of the shears is fastened by means of a screw 197 to the upper end of an arm 100 199. Rotatably mounted in spaced bearings in the upper end of the arm is a small vertical shaft 201 to the upper end of which the other blade 31 of the shears is fast. Fas- 105 tened to the small shaft 201 is a hub 203 having projecting from its side a pin 205 carrying a roll 207 which is received between the arms of a fork on the upper end of an arm 209. The arm 199 is loose on a rock- 110 shaft 211 while the arm 209 is fastened to said shaft by a pin 213. This rock-shaft has fast to it a handle 215 and is held in the angular position shown, with the handle against a stop 217, by means of a tension spring 219. The arms 199 and 209 are held in the relative angular position shown by compression 115 spring 221 which engages at its inner end a lug 223 on the arm 209, and, at its outer end, the end of a screw 225 which is threaded through the arm 199. A stop 227 formed on the arm 209 prevents the arm 199 from swinging forward in the position of parts shown in Fig. 4. When, now, the handle 215 is swung to the left the arms 209 and 199 swing to the left in unison until a hardened block 229 on the arm 199 contacts with a stop 231 carried by the frame of the machine. At this time the shears are open and have embraced the foxing strip. As the arm 209 swings fur- 120 ther to the left, during which time the spring 125 130

221 is compressed, the upright shaft 201 is rotated to swing the movable blade 31 of the shears toward the stationary blade so as to sever the foxing strip. As soon as the strip has been severed, the handle 215 is released and is returned to the position shown by the spring 219.

Assuming that a shoe has just been operated upon and that a portion of the free end of the foxing is depending from the end of the foxing guide 23, the operator presents a shoe to the machine in such manner as to cause the shoe to press the depending end of the foxing up against the indenting wheel 27. He then depresses the treadle to apply power to the driving shaft 107 and thereby actuate the hammers 33. There will be no movement of the winding-up reel, and consequently no feeding of the backing strip, and the foxing until the shoe is moved along to cause rotation of the indenting wheel. The operator then moves the shoe along until he has laid the foxing all around the bottom edge of the shoe or nearly all around as he may desire. During such movement the indenting wheel first presses the foxing progressively against the lower side portion of the shoe and immediately thereafter the hammers press it firmly into place and bend it about the lower edge of the shoe. All this time, it should be noted, practically no strain is put upon the foxing between the supply reel 7 and the point of application to the shoe nor is any slack formed in it, since the winding-up reel pulls the backing strip along at the same rate that the foxing is being applied to the shoe by the indenting wheel. When the desired extent of foxing has been laid in this manner, the operator removes the shoe from the indenting wheel and holds it in proper position for the severing operation. He then pulls forward the hand lever 215 whereupon the shears move forward until their blades are on opposite sides of the foxing and then the movable blade is operated to sever the foxing. The short length of foxing between the shears and the point where the foxing was last operated upon by the hammers is then laid by hand.

As described above, the indenting wheel contacts with the extreme margin of the foxing. It is sometimes desirable to cause the indenting wheel to contact with the foxing at a small distance from the edge thereof. In such case the bracket 35 (Fig. 2) is adjusted slightly to the left so that the indentations are spaced slightly from the edge of the foxing. In this case the extreme margin of the foxing is engaged and pressed against the shoe by a cylindrical portion 327 of the indenting wheel.

Although the invention has been set forth as embodied in a particular machine, it should be understood that the invention is not limited in the scope of its application to the par-

ticular machine which has been shown and described.

Having thus described my invention, what I claim as new and desire to secure by Letters Patent of the United States is:

1. A machine for applying foxing to a shoe having, in combination, foxing applying mechanism, a support for a supply of foxing, and means for severing the foxing. 70

2. A machine for applying foxing to a shoe having, in combination, foxing applying mechanism, a support for a supply of foxing, and operator-controlled means for severing the foxing. 75

3. A machine for supplying foxing to a shoe having, in combination, a support for a supply of foxing, foxing applying mechanism to which the foxing is led, said applying mechanism being adapted to receive foxing from the supply during the applying operation, and means for severing the foxing. 80

4. A machine for applying foxing to a shoe having, in combination, a support for a supply of foxing, foxing applying mechanism to which the foxing is led, said applying mechanism being adapted to receive foxing from the supply during the applying operation, foxing severing means normally inoperative, and operator-controlled means for rendering it operative. 90

5. A machine for applying foxing to a shoe having, in combination, a support for a supply of foxing, foxing applying mechanism to which the foxing is led, said applying mechanism being adapted to receive foxing from the supply during the applying operation, foxing severing means normally in inoperative position, and operator-controlled means for moving it into operative position and for causing it to sever the foxing. 95

6. A machine for applying foxing to a shoe having, in combination, a support for a supply of foxing, foxing applying mechanism to which the foxing is led, said applying mechanism being adapted to receive foxing from the supply during the applying operation, and a pair of shears located adjacent to the applying mechanism for severing the foxing. 100

7. A machine for applying foxing to a shoe having, in combination, a support for a supply of foxing, foxing applying mechanism to which the foxing is led, said applying mechanism being adapted to receive foxing from the supply during the applying operation, a pair of shears normally in inoperative position, and means for moving them into operative position and for actuating them to sever the foxing. 115

8. A machine for applying foxing to a shoe having, in combination, a support for a supply of foxing, foxing applying mechanism to which the foxing is led, said applying mechanism being adapted to receive foxing from the supply during the applying operation. 125

ation, a pair of shears for severing the foxing, a carrier for the shears arranged normally to hold the shears in inoperative position, means for moving the carrier to bring the shears into operative position, and means then becoming operative for closing the shears to sever the foxing.

9. A machine for applying foxing to a shoe having, in combination, a support for a supply of foxing, foxing applying mechanism to which the foxing is led, said applying mechanism being adapted to receive foxing from the supply during the applying operation, a pair of shears for severing the foxing, a carrier for the shears arranged normally to hold the shears in inoperative position, and an actuating member manipulation of which first moves the carrier to bring the shears into operative position and then causes the shears to sever the foxing.

10. A machine for applying foxing to a shoe having, in combination, a supply of foxing having a backing strip associated therewith, foxing applying mechanism, means for separating the backing from the foxing and for thereafter applying the foxing to the shoe, and means for severing the foxing.

11. A machine for applying foxing to a shoe having, in combination, a supply of foxing having a backing strip associated therewith, foxing applying mechanism, means for separating the backing from the foxing and for thereafter applying the foxing to the shoe, and a pair of shears located adjacent to the applying mechanism for severing the foxing.

12. A machine for applying foxing to a shoe having, in combination, a supply of foxing having a backing strip associated therewith, foxing applying mechanism, means for separating the backing from the foxing and for thereafter applying the foxing to the shoe, a pair of shears normally in inoperative position, and means for moving them into operative position and for actuating them to sever the foxing.

13. A machine for applying foxing to a shoe having, in combination, a supply of foxing having a backing strip associated therewith, foxing applying mechanism, and means for separating the backing from the foxing and for thereafter applying the foxing to the shoe.

14. A machine for applying a foxing to a shoe having, in combination, a supply reel for a coil of foxing having intercoiled therewith a backing strip, foxing applying mechanism to which the free end of the foxing is led, and means for separating the backing strip from the foxing before the foxing reaches the applying mechanism.

15. A machine for applying a foxing to a shoe having, in combination, a supply reel for a coil of foxing having intercoiled therewith a backing strip, foxing applying mechanism to which the free end of the foxing is led, a

winding reel, and means for separating the backing strip from the foxing before the foxing reaches the applying mechanism and for directing said strip to said winding reel.

16. A machine for applying foxing to a shoe having, in combination, a supply reel for a coil of foxing having a backing strip intercoiled therewith, foxing applying mechanism arranged when operated to take foxing from the reel, means for separating the backing strip from the foxing before the foxing reaches the applying mechanism, and means responsive to the operation of the applying mechanism for exerting a pull on the backing strip to cause it to move at substantially the same speed as the foxing is moved during its application to the shoe.

17. A machine for applying foxing to a shoe having, in combination, a supply reel for a coil of foxing having a backing strip intercoiled therewith, foxing applying mechanism arranged to take foxing from the reel when a shoe is moved in proper relation to the applying mechanism, and means responsive to such movement of the shoe for exerting a pull on the backing strip to cause it to move at substantially the same speed as the foxing is moved during its application to the shoe.

18. A machine for applying foxing to a shoe having, in combination, a supply reel for a coil of foxing having a backing strip intercoiled therewith, foxing applying mechanism including a wheel arranged to take foxing from the reel when the wheel is rotated, means for leading the strip away from the foxing before the foxing reaches the applying mechanism, and means responsive to rotation of said wheel for causing the strip to be pulled from the supply reel at a speed substantially equal to the peripheral speed of the wheel.

19. A machine for applying foxing to a shoe having, in combination, a supply reel for a coil of foxing having intercoiled therewith a backing strip, foxing applying mechanism including a rotary member which serves to press the foxing against a shoe moved in proper relation to it, a second rotary member over which the backing strip runs, and connections between the two members such that, when the first-named member is rotated by engagement with the shoe, the second-named member is rotated at substantially the same peripheral speed.

20. A machine for applying a foxing to a shoe having, in combination, a supply reel for a coil of foxing having intercoiled therewith a backing strip, foxing applying mechanism, a winding reel, means for directing the foxing to the applying mechanism, means for separating the backing strip from the foxing before it reaches the applying mechanism and directing it to the winding reel, and

feeding means for the strip operated by rotation of the winding reel.

21. A machine for applying a foxing to a shoe having, in combination, a supply reel for a coil of foxing having intercoiled therewith a backing strip, foxing applying mechanism, means for separating the foxing from the backing strip and for directing the free end of the foxing to the applying mechanism, a winding-up reel for the backing strip, and friction means for rotating the last-named reel.

22. A machine for applying a foxing to a shoe having, in combination, a supply reel for a coil of foxing having intercoiled therewith a backing strip, foxing applying mechanism, means for separating the foxing from the backing strip and for directing the free end of the foxing to the applying mechanism, a winding-up reel for the backing strip, and friction means for rotating the last-named reel, said friction means having a force insufficient to rotate the winding-up reel except when foxing is being applied to a shoe.

23. A machine for applying foxing to a shoe having, in combination, a supply reel for a coil of foxing having a backing strip intercoiled therewith, foxing applying mechanism arranged to take foxing from the supply reel and apply it to the shoe, a strip-winding reel, means including feed rolls and a strip-feed governing roll for directing the strip to the winding reel, means for rotating the feed rolls from the winding reel, means for rotating the strip-feed governing roll from the foxing applying mechanism, and friction means adapted to exert upon the winding reel a force slightly less than that required to rotate it whereby, when a shoe is presented to the applying mechanism and moved to cause foxing to be applied to it, the winding reel is rotated to wind up backing.

24. A foxing applying machine having, in combination, means for guiding a strip of foxing to the lower marginal face of a shoe with a margin of the foxing projecting beyond the bottom of the shoe, and means for hammering the foxing into place, said means including a hammer of rigid material and a spring for permitting the hammer to yield.

25. A foxing applying machine having, in combination, means for guiding a strip of foxing the lower marginal face of a shoe with a margin of the foxing projecting beyond the bottom of the shoe, and means for hammering the foxing into place, said means comprising a rotary head and a hammer yieldingly carried thereby.

26. A foxing applying machine having, in combination, means for guiding a strip of foxing to the lower marginal face of a shoe with a margin of the foxing projecting beyond the bottom of the shoe, and means for hammering the foxing into place, said means

comprising a rotary head and a hammer yieldingly and pivotally carried thereby.

27. A foxing applying machine having, in combination, means for guiding a strip of foxing to the lower marginal face of a shoe with a margin of the foxing projecting beyond the bottom of the shoe, and means for hammering the foxing into place, said means comprising a rotary head and a plurality of spaced hammers yieldingly carried thereby.

28. A foxing applying machine having, in combination, means for guiding a strip of foxing to the lower marginal face of a shoe with a margin of the foxing projecting beyond the bottom of the shoe, and means for so hammering the foxing into place, said means comprising a rotary head and a plurality of spaced hammers yieldingly and pivotally carried thereby.

29. A machine for applying foxing to a shoe having, in combination, guiding means for the foxing constructed and arranged to permit a shoe to be presented in position to have the foxing laid along its lower margin, and means for hammering the foxing into place, said means comprising a rotary head and a hammer yieldingly carried thereby.

30. A machine for applying foxing to a shoe having, in combination, guiding means for the foxing constructed and arranged to permit a shoe to be presented in position to have the foxing laid along its lower margin, and means for hammering the foxing into place, said means comprising a rotary head and a plurality of spaced hammers yieldingly carried thereby.

31. A machine for applying foxing to a shoe having, in combination, guiding means for the foxing constructed and arranged to permit a shoe to be presented in such a manner as to have the foxing laid along its lower margin, and means for hammering the foxing into place, said means comprising a rotary head, a hammer pivoted to the head, a spring tending at all times to swing the hammer about the pivot and a stop for determining the normal position of the hammer with respect to the head.

32. A machine for applying foxing to a shoe having, in combination, guiding means for the foxing constructed and arranged to permit a shoe to be presented in such manner as to have the foxing laid along its lower margin, and means for hammering the foxing into place, said means comprising a rotary head, a plurality of hammers pivoted to the head and spaced from each other in the direction of rotation of the head, springs tending at all times to swing the hammers about their pivots, and stops for determining the normal positions of the hammers with respect to the head.

33. A machine for applying foxing to a shoe having, in combination, guiding means for the foxing arranged to permit a shoe to

be presented to it in such manner as to have the foxing laid along its lower margin with a portion of the foxing projecting beyond the bottom of the shoe, and means for hammering the foxing into place, said means including a hammer of rigid material and means for causing the hammer first to strike the foxing where it lies on the margin and then to bend the projecting portion about the lower edge of the shoe and press it against the bottom thereof.

34. A machine for applying foxing to a shoe having, in combination, a guide for the foxing, and an indenting wheel having teeth arranged to co-operate with the guide to engage and hold the free end of the foxing in such position before the shoe is presented to the wheel that, when the shoe is subsequently presented to the indenting wheel and moved along, foxing will be fed to the shoe.

35. A machine for applying an adhesive strip to a piece of work and for severing the strip having, in combination, means for applying the strip to the work, means for there-after pressing the strip firmly against the work, a pair of shears normally closed and located at one side of the strip, and operator-controlled means acting first to open the shears and move them into operative position, then to close them to sever the strip, and finally to return them to initial closed position.

In testimony whereof I have signed my name to this specification.

LEWIS J. BAZZONI.

CERTIFICATE OF CORRECTION.

Patent No. 1,753,497.

Granted April 8, 1930, to

LEWIS J. BAZZONI.

It is hereby certified that error appears in the printed specification of the above numbered patent requiring correction as follows: Page 7, line 53, claim 25, after "foxing" insert "to"; and that the said Letters Patent should be read with this correction therein that the same may conform to the record of the case in the Patent Office.

Signed and sealed this 16th day of December, A. D. 1930.

(Seal)

M. J. Moore,
Acting Commissioner of Patents.
